(57) **CLAIM**

The ornamental design for a sliding computer mouse as shown and described.

DESCRIPTION

1. Sliding computer mouse

A sliding computer mouse.

Fig. 1.1 is a perspective view of the sliding computer mouse.

Fig. 1.2 is a front view thereof.

Fig. 1.3 is a back view thereof.

Fig. 1.4 is a left view thereof.

Fig. 1.5 is a right view thereof.

Fig. 1.6 is a top view thereof.

Fig. 1.7 is a bottom view thereof.

The features shown in broken lines in the drawing depict portions of the sliding computer mouse and form no part of the claimed design.
